UNITED STATES PATENT OFFICE.

SEYMOUR W. BONSALL, OF NEW YORK, N. Y.

WARDROBE OR SHOW-CASE.

SPECIFICATION forming part of Letters Patent No. 760,727, dated May 24, 1904.

Application filed February 18, 1904. Serial No. 194,306. (No model.)

To all whom it may concern:

Be it known that I, SEYMOUR W. BONSALL, a citizen of the United States, residing in the city, county, and State of New York, have invented a certain new and useful Improvement 5 in Wardrobes or Show-Cases, of which the following is a specification.

This improvement has particular relation to means whereby certain forms of closets, 10 wardrobes, and show-cases are made convenient and available for the suspension therein of various articles, such as garments and the like, while permitting easy access and full inspection of the garments or other articles, 15 which would otherwise not be possible.

The improvement is applicable in some of its forms to use in wardrobe-trunks.

This improvement is particularly useful in making convenient and available for the suspension of garments those spaces which would otherwise be so low as to be unsuited to this 20 purpose. Where a closet is so low that a man or woman is obliged to lean over in order to look into it, it is not convenient for the suspension of garments and the like on account 25 of the difficulty in picking out the particular clothing desired at any time and because the user must either stoop down in order to see the hooks or must grope about for the hook 30 required.

In my United States Patent No. 642,075 I have shown a device applicable to any closet which permits the clothing to be drawn forward into sight when any particular garment 35 is desired and also facilitates the hanging up and inclosing of garments in a manner to preserve the desired folds and prevent mussing. This device is particularly suitable to deep and narrow closets for wardrobes, but is not 40 so useful in connection with wide and shallow closets.

The present improvement will be found particularly advantageous in those spaces which are otherwise too low for convenient 45 suspension of the garments and are too shallow and wide to develop the full convenience of the device described in my aforesaid Letters Patent. There are many instances where a space of this kind can be very conveniently

combined with a sideboard or bureau with or 50 without a mirror above the space in question, and hitherto such spaces have not been capable of employment for hanging garments conveniently.

The present improvement is applicable not 55 only in the particular cases above set out, but in many other localities where other forms of suspending means are not convenient.

In two other applications for patent filed concurrently herewith I have described a tilt- 60 ing or rocking support for garments whereby they can be easily drawn forward into view, which devices are suitable for use with forms of hangers which accommodate themselves to angular changes in the position of the sup- 65 porting means. My present invention is adapted for use with those forms of hanger which do not thus accommodate themselves, but are best used in such a manner as to preserve substantially the same angle with the 70 horizontal at all times.

A preferred form of my present invention is shown in the accompanying drawings, where- 75 in—

Figure 1 is a perspective view of a ward- 75 robe opened so as to show the arrangement of my apparatus within it, and Fig. 2 is a vertical median section of the same with the door removed.

Any convenient form of wardrobe or closet 80 is shown at 1, the same being preferably provided with any desired form of door or doors 2. Within this wardrobe there is mounted a movable hanger-support 3, which may assume many different forms, but which comprises in 85 the form shown two side pieces and a back piece 4, which latter can be pushed back against the back of the wardrobe or any appropriate abutment supplied for the purpose. This hanger-support may be combined with 90 any desired form of hanger and is particularly adapted to the support of the hangers shown in the drawings which are intended for the support of trousers or the like and are constructed in accordance with the description in 95 my United States patent for garment-hangers, No. 724,427. These hangers comprise se- curing-bars 5, pivoted to clamps 6, which are

removably supported and are capable of moving on the slide 7, fixed to the hanger-support 4. It is obvious that it would not be convenient to arrange hangers of this description on a rocking support which when operated acted to bring the bars 5 out of the horizontal. It is also clear that in order to best accomplish the ends of this invention it is desirable to place the bars 5 as far forward as possible and that in this position the weight of the trousers would tend to jam a sliding support of any kind. The objection last noted is not found in the construction which I have adopted for the purposes of this invention. This construction involves two separate standards for supporting each side of the hanger-support 4, which standards, as shown at 8 and 9, are pivoted to the hanger-support at their upper ends and to appropriate fixtures 10 and 11 at their lower ends. This arrangement preserves the horizontal position of the hanger-support 4 whatever its location within or outside of the wardrobe. As shown in dotted lines in Fig. 2, the hanger-support is sustained in its extreme inward position by resting against the back of the wardrobe. In its forward position a projection 12 comes in contact with a fixed stop 13, so that further movement forward is prevented. By making the standards 8 and 9 sufficiently long the vertical movement of the hanger-support can be made as small as desired, and the effort necessary for moving this support in and out can be thus reduced.

This device is particularly suitable to those closets or wardrobes which are not much more than deep enough to accommodate the width of the clothing and are at the same time wide enough to permit a large number of garments to be placed flat the one next the other. In any form of closet, however, and whatever the form of hangers used this device will be most useful when for any reason it is not convenient to enter or look into the space where the garments are hung. In such a case access is very easily had to all the garments at once by use of the device above described. All that is necessary is to draw the hanger-support forward into the position shown, so that the garments are brought for-

ward of the closet-doorway where they may be easily separated and distinguished.

While various forms of hanger-support are within the scope of this invention, I prefer the form shown, in which the two side pieces 3 fit within the sides of the closet and are fixed at right angles to the two ends of the back piece 4, which carries the hangers. The standards 8 and 9 are then pivoted to these side pieces, as shown in the drawings, and the back piece being fastened to the hangers directly it is possible to push said hangers back farther into the closet than if they were secured farther forward on the hanger-support.

A variety of changes may be made in this invention without departing from its spirit and scope, and I am not to be understood as limiting myself to the details herein shown and described.

What I claim is—

1. In a device of the class described, a receptacle, a pair of pivoted standards placed on each side thereof, a hanger-support pivoted to, and supported between said pairs of standards and extending at right angles to the planes in which said standards move, hangers extending horizontally forward from the front of said hanger-support, and a stop for limiting forward movement of said hangers when brought into view in front of the receptacle; substantially as described.

2. In a device of the class described, a receptacle, a hanger-support within the same extending from side to side of the receptacle and comprising side pieces and a back piece fixed at right angles between them, a pair of tilting standards pivoted to each of said side pieces, each standard being also pivoted at its lower end within said receptacle, sliding hangers mounted on said hanger-support so as to extend forward horizontally, and a stop to limit the forward movement of the hangers when brought into view outside of the receptacle; substantially as described.

SEYMOUR W. BONSALL.
